JÖRGN REMMEN, OF PITTSBURGH, PENNSYLVANIA, ASSIGNEE TO GEORGE E. HADD, TRUSTEE, OF PITTSBURGH, PENNSYLVANIA.

INTERNAL-COMBUSTION ENGINE.

1,288,900.

Specification of Letters Patent. Patented Nov. 5, 1918.

Application filed July 17, 1912. Serial No. 108,220.

To all whom it may concern:

Be it known that I, JÖRGN REMMEN, a resident of Pittsburgh, in the county of Allegheny and State of Pennsylvania, have invented a new and useful Improvement in Internal-Combustion Engines, of which the following is a specification.

This invention relates to four-cycle explosive engines, or internal combustion engines, and the purpose is to provide such an engine which will be thoroughly scavenged by air forced through the explosion chamber, in which the valves controlling the parts to the cylinders will be air cooled, in which all charges will be under uniform compression at the time of explosion, which may be started by compressed air so applied as not to interfere with the explosive charges, which will constantly compress and distribute air to secure the above mentioned and other results, which will store air for starting, and in which the air storing means may be used as a brake on the engine.

To secure these and other objects special arrangements and constructions of valves and air passages are provided, as will more fully appear hereinafter. The desired results are attained by the use of a double-bore cylinder, with a piston working in each bore, providing an explosion chamber, and an air compression chamber which are simultaneously opened and closed by the pistons. Air from a storage tank is distributed by special valve mechanism to move the engine until explosions occur to start it by its own power, and after starting the air from the compression chamber is distributed to cool the exhaust port, the interior of the cylinder, and the inlet port, as well as to scavenge the cylinder during the exhaust stroke succeeding an explosion, and to admit air under pressure to the explosion chamber during the stroke which compresses the explosive charge, all of which will appear more fully throughout the specification. By the arrangement here provided the normal operation of the explosion parts of the engine are in no way interfered with by the air storing, compressing, and distributing parts, so that while these are being used for starting the engine, the explosions can occur simultaneously therewith, and thereby insure the quick starting of the engine by its own power.

In the accompanying drawings, Figure 1

is a vertical section, in part a diagram, 55 through the center of one of the cylinders, showing the relative position of all parts at the end of the charge compressing stroke and at the beginning of a working, or explosion stroke of the piston; Fig. 2 is a view similar to that of Fig. 1, but showing the parts in relative position near the end of a scavenging stroke of the piston; Fig. 3 is a partial vertical section showing details of the air distributing valve; Fig. 4 is a detail view of the rotary shaft of the distributing valve, on a reduced scale; Fig. 5 is a horizontal section through one of the piston valves, on the line 5—5 of Fig. 2; Fig. 6 is a partial section showing details of the balanced pressure valve adapted to adjust the distributing valve to running or starting position; Fig. 7 is a vertical section through the distributing valve showing the parts thereof in position for starting the engine by compressed fluid; Fig. 8 shows a vertical section through the distributing valve, the parts thereof being set in normal running position, and the whole figure constitutes a diagram indicating the relative positions at all times of the distributing valve parts and the engine shaft and piston; and Fig. 9 is a diagram showing the connection of air from the storage tank to the engine, and from the engine to the tank to store air after the engine is running, and includes details of a valve controlling the tank, and of operating means for coupling the air supply to the engine.

As shown in Figs. 1 and 2, the engine comprises a cylinder 1 having bores of different diameters, namely, a small bore 2 which constitutes the explosion chamber, and a larger bore 3 which constitutes the chamber in which fluid pressure acts to start the engine, and also forms a compression chamber for air for scavenging, cooling, and storage, as will hereinafter appear. Working in this cylinder is a piston 4 having a smaller head 5 fitting the bore 2, and a larger head 6 fitting the bore 3. This piston is connected by the usual rod 7 to a crank 8 on the main shaft 9 which is mounted in the crank case 10 as is usual with such engines. The cylinder walls are preferably cast with exterior fins 11, for the purpose of radiating heat, as is used in air-cooled engines, but a water jacket may be used if desired; the explosion chan-

ber is provided with the usual spark plug; the pistons are provided with packing rings 13, and suitable oil supply grooves. An inlet port and an exhaust port are provided 5 at the top of the explosion chamber.

The inlet port 14 leads by a pipe 15 to a carburetor and source of fuel. This inlet port is formed by an opening through a bushing, or lining 16 in a small supplementary cylinder 17, cast integral with the explosion cylinder, and axially parallel thereto. The cylinder 17 is enlarged about its upper end to form a chamber 18, which opens directly into the explosion chamber, 15 and forms a passage for fluid admitted to the explosion chamber by the inlet port. The shell 16 is cut away except for two or more supporting portions, thus forming a free substantially annular opening through 20 the lining to the explosion chamber. This inlet port is controlled by a piston valve reciprocated in the inlet cylinder, comprising the valve head 19, a hollow cylindrical shell 20, having interior ribs 21, and having the 25 wall 20 cut away to form an annular opening 22 near its head, and a similar opening 23 near its base. The ribs 21 connect the head, wall, and base, so that the openings may be made continuous around the shell, 30 and therefore give free passage to fluid therethrough. The lining 16 is cut away to form an opening 24, which is adapted to register with the opening 23 in the valve piston, in certain positions of the latter. The 35 opening 24 leads into a chamber 25, which surrounds the lining 16, and the smaller bore of the main cylinder, and opens into the larger bore 3 of the main cylinder, that is, the air compression chamber.

The exhaust port comprises a substantially 40 annual opening 26 through a lining 27 in the supplementary valve cylinder 28 cast with the main cylinder, and axially parallel thereto. This supplemental cylinder has an 45 enlarged portion forming the supplementary chamber 29, which surrounds the lining 27, and opens into the explosion chamber of the main cylinder. The lining 27 connects with a pipe 30, leading to a muffler, or to free air.

Openings 31 through the walls of cylinders 50 55 and 28 provide means for oiling. The exhaust port 26 is controlled by a piston valve, which comprises a cylindrical shell 32, having interior ribs 33, and an annular opening 34 through the cylinder wall near the base. This piston valve is open at its free end, terminating in a choked portion 35. The lining 27 has an annular opening 36 near the base of the piston valve 32, and adapted to 60 register with the opening 34 therein during certain positions of the valve, as will be hereinafter described. A chamber 37 surrounds the lower end of the lining 27 and the opening 36 therethrough.

The chamber 25 extends entirely around 65

the main cylinder and the supplementary valve cylinders, as above described. It is separated from the chamber 37, which surrounds the cylinder of the piston valve controlling the exhaust port, by a wall 38. The 70 lining 27 is joined to a casting 39, which forms a part of the crank case of the engine, and extends the entire length thereof. The casting 39 comprises an inner wall 40, a dividing partition 41, and an outer wall 42, 75 forming extensions from the chambers 25 and 37. The inner and outer walls are connected by a partition 41^a below the partition 41, forming a lower chamber 43, which extends the entire length of the casting 39, 80 and is connected through the distributing valve to all of the cylinders comprising the engine, as later described. The chambers 25 and 37 are individual for each cylinder. The opening between the chambers 25, 37 and 85 43 is controlled by a sleeve 44, having openings 45, 46 and 47 therethrough, and a valve shaft 48 rotatable therein. The walls of casting 39 and the partition 41, form the bearing for the said sleeve, which is rotatable. This 90 sleeve and valve shaft, with the chamber connections thereto, comprise the distributing valve referred to throughout the specification.

The piston valves controlling the inlet 95 and exhaust ports to the explosion chamber and the air distributing valve are operated by positive driving connection to the main shaft. This is diagrammatically shown in Figs. 1 and 2, which may be taken to represent a gear wheel 49, on the main shaft, engaging a gear wheel 50, on a shaft 51, having a crank 52, to which is attached a rod 53, connected to the piston valve. The gear wheel 49 also engages a gear wheel 54 fixed 100 on a shaft 55, carrying a crank 56 to which is attached the rod 57 connected to the piston valve 32, controlling the exhaust port. The shaft 55 carries a gear wheel 58 which connects with a gear wheel 59 fixed on the 105 valve shaft 48. The main shaft rotates clockwise, consequently the cranks reciprocating the valve pistons are rotated counterclockwise, and the valve shaft 48 clockwise, as will be obvious. The diameter 110 of gear wheel 49 is one half that of gear wheels 50 and 54, consequently the reciprocation of the piston valves requires double the time of the reciprocation of the engine piston. The diameter of gear wheels 58 and 59 is the same, consequently the valve shaft 48 is rotated at one half the speed of the main shaft 9, and in the same direction.

In Figs. 3 and 4 details of the distributing valve are shown. The sleeve 44 is carried in the bearing formed by the casting 39, as shown in Fig. 3, and in the several sectional views of the distributing valve. It has at one end an extension 60, which carries a gear wheel 61, adapted to rotate the sleeve, 115

as later described. In practice a bushing may be used between the sleeve 44 and the casting 39, but for the purposes of this description there is no need to show such details. The openings 45, 46 and 47 extend through the wall of the sleeve, the opening 47 being shown in Fig. 3, and the others in the several sectional views. The shaft 48 is rotatably mounted in the sleeve 44, and is held in place by collars 62 engaging an annular flanged member 63 attached to the casting 39. The shaft has an extension 64 beyond the sleeve, and upon this is fixed the driving gear wheel 59, which engages the gear wheel 58, as above described. The shaft 48 has passages 65, in the form of notches, cut therein. These passages are adapted to register with the openings 45, 46 and 47 of the sleeve 44, as the shaft rotates.

It will be understood that explosive engines are usually built with a plurality of cylinders in pairs, such as two, four, six, eight, twelve, etc. My invention is adapted for any number of cylinders, and the only modification necessary for different numbers of cylinders is in the construction of the distributing valve. The chamber 43 extends the entire length of the engine, and connects with each of the cylinders through the distributing valve. In Figs. 3 and 4 I have illustrated a construction adapted for a four-cylinder engine, in which it is customary to set the cranks on the main shaft at an angle of 180 degrees, so that there will always be one piston driving. The passages 65 through the shaft of the distributing valve are therefore in this case set at an angle of 90 degrees to each succeeding passage, corresponding to the arrangement of the pistons, and order of explosions, in the four cylinders. It will be readily understood that in a six-cylinder engine the cranks would be arranged at angles of 120 degrees on the main shaft, and an explosion would occur at each 120 degrees of revolution thereof. Consequently the passages 65 in my distributing valve shaft would be set at angles of 60 degrees from each other corresponding to the angularity of the cranks of the respective pistons of the cylinder with which the respective passages 65 were adapted to cooperate.

A pipe 66 leads from the chamber 43 through a three-way valve to a storage tank 67. The three-way valve construction is not peculiar to this invention and is well known. It consists of a casing 68, a valve 69 rotatable therein, and having openings 70, 71 and 72 therethrough. The casing has an inlet 73, and an outlet 74 for the pipe 66, and an opening to the atmosphere 75. A lever 76 is adapted to turn the valve to connect the various openings, as will be readily understood. A spring 77 connected to one end

of the lever is adapted to throw the valve into normal position in which the opening 71 registers with the inlet 73 and the opening 72 registers with the free port 75, the outlet 74 to the tank being closed. A connecting member 78 leads from the other end of the lever to a handle 79, or other manually or foot operated means for throwing the valve into the position shown in Fig. 9, which is the starting position of the valve. A spring 80 may be provided to return the pedal, or handle 79, to normal position when the valve is released.

The tank 67 is connected by a pipe 81 to a balanced pressure valve mechanism adapted to rotate the sleeve 44 from its normal running position to the position occupied while the engine is being started by fluid pressure. The details of this balanced valve are shown in Fig. 6, and comprise a casing 82 having a cylindrical bore 83, with a plunger 84 mounted therein and having an enlarged portion 85, forming a shoulder 86 adapted to abut the edge of said cylinder, and so to limit travel of the plunger in one direction. A coiled spring 87 is retained in the bore by a terminal screw cap 88, and this spring bears against the end of the plunger 84, tending to push it out of the bore. The enlarged portion of the plunger works in a second cylinder 89, and the head of the plunger has a small central terminal abutment 90 adapted to contact with the end wall 91 of the chamber 89. Therefore the travel of the plunger is limited by abutment of the shoulder 86, and the extension 90, as above described. The plunger is provided with a rack 92 engaging gear wheel 61 attached to the sleeve 44. Consequently the reciprocation of the plunger will turn the sleeve of the distributing valve, and the travel of the plunger is so limited that its movement is just sufficient to throw the sleeve 44 from normal running position, as shown in Fig. 8, to starting position, as shown in Fig. 7, and as is more fully described elsewhere. The chamber 89 is connected by a passage 93 to an auxiliary bore 94, which in turn is connected to pipe 81 leading to the tank 67. A plunger, or valve 95, works in the chamber 94, and has a beveled head, cut away on the under side, at 96, with an annular groove 97 extending therearound, so that in normal position, as shown in Fig. 6, there is a passage for air from pipe 81 into the chamber 94 and around the plunger 95 through the passage 93 into the chamber 89, holding both plungers seated against the pressure of their respective springs. The plunger 95 has an axial bore 98, which has a vertical terminal opening 99 adapted to register with the passage 93 when the plunger is pushed inward to abut the end wall of the chamber 94. The outer end of the plunger is slotted, forming a fork 100, and the bore 98 opens into this slot, to the

atmosphere. An arm 101 extends from the end of the casing 82 ending in a fork 102, having a downward extension 103 forming an outer bearing for the plunger 95, which 5 has another bearing formed by an extension 104 of the casing 82, the latter extension carrying a screw cap 105 and a packing member 106. A coiled spring 107 engages an annular collar 107^a on the plunger, and has its 10 other end abutting an adjusting screw 112 in the outer bearing 103, thus exerting a constant inward pressure on the plunger. A lever 108 is fulcrumed by pin 109 through the fork 102, and has one end connected to a 15 link 110, and its other end connected by a pin to the fork 100 of the plunger 95. A suitable packing 111 is provided around the large plunger 85.

The operation of this balanced pressure 20 valve will be readily understood, and is as follows:—Air from the tank through pipe 81 enters the chamber 94 and presses against the end of the plunger 95, forcing it outward in opposition to the spring 107. The pressure 25 of this spring is adjusted, and set to the required degree by means of the bearing nut 112. When the plunger is forced back by pressure of air to its normal position, as shown in Fig. 6, air passes around the plunger 30 head and into the chamber 89, forcing the large plunger 84 inward as opposed to the spring 87, to the position shown in Fig. 6, which is normal when the engine is running. This rotates the valve sleeve 44 to 35 normal running position, and holds it there so long as air pressure is up to the fixed minimum point. When pressure in the tank falls, the spring 87 tends to force the plunger 84 outward, to the position limited by 40 the wall 91. But it is desirable that this movement should be quick, so that the distributing valve sleeve may be changed from one position to the other at one movement. This is accomplished by means of the auxiliary plunger, which is in effect a pilot 45 valve. Being of smaller diameter, this smaller valve works through its packing easily, and when the air pressure falls the spring 107 readily forces it inward to the 50 position determined by abutment with the end wall of chamber 94, as shown in Fig. 9. In this position chamber 89 is shut off from the air supply and the passage 93 registers with the passage 99, thus releasing the pressure 55 in chamber 89, by opening it to the atmosphere. Consequently the smaller plunger will operate before the larger starts to move at all, and as soon as the opening 99 registers with passage 93, the air pressure on 60 plunger 85 will be entirely removed, and spring 87 will quickly throw it out of the normal position shown and into the position limited by contact with the wall 91, as shown in Fig. 9. This changes the distributing 65 valve so that air is pumped directly from the

engine to the tank until the pressure is raised to the required point, as will be more fully described below.

The lever 108 is connected by link 110, and any form of connection 113 to the handle 79. This member, which may be in any other desired form, such as a foot pedal, is located at a convenient point, and is manually operated when it is desired to start the engine. When operated the three-way valve 75 is thrown into the position shown in Fig. 9, permitting passage of air from the tank to the chamber 43, the plunger 95 is forced inward to its limiting position, thus releasing pressure on the plunger 85, and allowing 80 the sleeve of the distributing valve to be thrown into starting position, as shown in Fig. 7.

A pipe 114 leads from the tank to a chamber 115 which has a port 116 connecting with the chamber 25, controlled by a shifting valve 117, permitting passage of air from the chamber 25 to chamber 115, but being closed against return. See Fig. 2.

The operation of the engine is as follows:—

Supposing the starting tank to be charged with compressed air, as it normally will be, the engine is started by pulling the button 79, thus throwing the three-way valve into the 95 position shown in Fig. 9, allowing passage of compressed air from the tank to the chamber 43. At the same time the lever 108 is actuated, and the balanced pressure valve mechanism operates as above described to 100 throw the distributing valve sleeve into the position shown in Fig. 7. Presuming that one of the pistons is in a position representing the charging stroke, that is, moving downward on the cycle which normally 105 draws an explosive charge into the explosion chamber, as will always be the case with one piston of a four-cycle engine comprising four or more cylinders, the throwing of the distributing valve sleeve to the starting 110 position and admission of air pressure to chamber 43, will permit the transfer of pressure from chamber 43 through the distributing valve by way of passages 47, 65 and 45, to the chamber 25, which opens into 115 the larger bore of the cylinder, and so expose the larger piston head to air pressure. Consequently the piston will be forced downward through what corresponds to the charging or induction stroke of the engine. 120 By the time that particular stroke has been completed, the valve 48 will have turned through 90 degrees, closing the passage of air to the cylinder of the piston first actuated, and admitting air to move the piston following the first at an angle of 180 degrees, and so on, continuously, one piston after another being actuated by the air pressure. It will be seen that this air is supplied in such manner as not to interfere 125 130 135

with the explosion chamber in any way, and at the end of the stroke is exhausted through port 118, consequently the throttle and spark control having been properly set, an explosion should be obtained during movement of the first piston actuated. If this is not so, however, the engine will be actuated by air pressure continuously until an explosion does occur, and the engine starts of its own power. As soon as this results, the operator releases the handle 79, the three-way valve is returned to normal position, shutting off the tank entirely, and opening the chamber 43 to free air through the port 75. At the same time the lever 108 of the balanced pressure valve is released, and that mechanism will throw the sleeve 44 into the normal running position, as shown in Fig. 8, as soon as pressure in the tank is restored to normal by the pump action of the running engine.

The engine is of the four-cycle variety, having a charging stroke in which explosive gas is drawn into the cylinder, a compression stroke in which the charge is reduced to a small volume, an explosion, or working stroke during which the piston is actuated by explosion of the compressed charge, and a scavenging stroke, during which the burnt gas is driven from the explosion chamber by return of the piston. The piston 6 working in the air compression bore 8 will similarly have two compression, and two suction strokes. By the valve mechanism provided, while the engine is running by explosions, the air compressed in the bore 8 will be forced through the inlet valve and the explosion chamber during the scavenging stroke, and will be forced through the hollow valve controlling the exhaust port, during the compression stroke.

More particularly the operation of the engine, while running by explosion, is as follows:—

Referring to Fig. 1, which shows the relative position of parts with the piston at its top (or zero position on the diagram), at the end of the compression stroke, and the beginning of the working or explosion stroke. In this position the space above the piston head 5 is filled with a charge of compressed gas, the main shaft is rotating clockwise, and the piston is ready to move downward. The explosion occurs as the piston moves downward; air is supplied to the larger bore through the distributing valve, which is open as shown. The inlet port is closed by its piston valve which is moving upward; the exhaust port is closed by its piston valve which is in raised position, but moving downward.

At the time the piston reaches its lower limit, at the end of the explosion stroke, the valve 32 will have moved downward to open the exhaust port 26, so that as the piston

again moves upward, on the scavenging stroke, the burnt gases pass freely out the exhaust port. The piston valve 20 reaches its upper limit during the downward travel of the main piston on its explosion stroke 70 and then moves downward during the scavenging stroke. Air supplied through port 118 is trapped in the bore 8, the distributing valve having turned so that there is no escape therethrough from chamber 25, and consequently it is compressed until the annular opening 22 in the piston valve 20, during its downward movement, registers with the inlet opening 14. At the same time the opening 23 in said piston valve will register 80 with the opening 24 in the cylinder lining, and air which is under pressure in the bore 8 and chamber 25 will escape through the openings 24, 23, the hollow piston, and the openings 22 and inlet port 14, through the top of the explosion chamber and out the exhaust port, thus driving out all of the burnt gases, and cooling the interior of that chamber and the top of the exhaust valve.

As the piston reaches the top of this scavenging stroke the piston valve 22 has moved upward again closing the exhaust port, and the piston valve 20 has moved downward leaving the inlet port 14 freely connected to the fuel supply pipe 15. Consequently the next downward stroke of the piston, the charging stroke, draws fuel through the inlet port to fill the explosion chamber. The distributing valve has turned through another 90 degrees so that the chamber 25 does not connect with chamber 43, and therefore during this stroke no air is supplied to the larger bore, which therefore contains a partial vacuum. However, an opening 113 in the lower end of the large bore 8 relieves this condition as soon as the piston head 6 passes below said opening.

As the piston again starts upward, on the compression stroke, the exhaust port is still closed, the piston valve 20 has reached its lower limit, and moved upward, closing the inlet, so that the charge of explosive gas is trapped in the cylinder, and compressed by this up stroke. During a part of this stroke the opening 22 registers with the inlet port 14, and at the same time the opening 23 registers with the opening 24 from the air chamber 25, consequently air which is being compressed in the bore 8 passes into the explosion chamber, and adds to the volume of the charge. This insures uniform compression of the explosive charge, under all conditions, regardless of the position of the throttle, as will be more fully described later. During another part of the compression stroke the distributing valve is in a position allowing air to pass from chamber 25 to chamber 27, and at this stage the opening 24 of the valve piston 20 registers with the opening 26 through the lining 16, and the

so the remainder of the air compressed in the larger bore escapes through the piston valve controlling the exhaust port, and cools that part of the engine.

5 The cycles are then repeated. It will be understood that these cycles occur continuously in each cylinder, and follow each other at regular intervals, determined by the angularity of the attachment of the pistons 10 to the crank shaft, which in turn is determined by the number of cylinders.

Fig. 8 shows diagrammatically the relation between the engine piston, and the distributing valve, at any particular stage of 15 any cycle. As shown, the circle at the right represents the main crank shaft, the arrow being pointed to zero position indicating that the particular piston being traced is at the top of one of its strokes, and in this 20 diagram it may be taken that the piston is just entering upon the charging or induction stroke. That is, when one of the pistons is at the top, ready to start upon the charging stroke, the distributing valve co- 25 operating with that cylinder will be in the position shown at the left of the diagram, which also shows the sleeve in normal running position. The rotation of the distributing valve shaft is at one half the speed 30 of rotation of the crank shaft. Consequently at the end of the charging stroke the piston having reached its bottom position, and having passed through 180 degrees, the rotary valve shaft will have turned 35 through 90 degrees, and the arrow on the valve stem will point to the 180 degree mark at the top of the diagram, and so on, the valve shaft turning from the position shown at one half the speed of the crank shaft.

40 By this diagram the position of the valve at any particular stage of any cycle may be readily determined. When the engine is to be started by air pressure the distributing valve sleeve is turned to the point marked 45 "Starting position" on the diagram, which will cause a different distribution of the air, and this also may be readily traced by following the rotation of the crank and valve shafts on the diagram.

50 When the pressure in the tank falls so low that the balanced valve mechanism above described operates to throw the sleeve into starting position, as shown on Fig. 7, the distributing valve will then entirely prevent 55 the passage of air from the chamber 25 to the chamber 37 during the compression strokes of the piston 6. Consequently air during those strokes will be trapped, and the only escape from the chamber 25 will be 60 through the snifting valve 117 and through the pipe 114 to the tank. Consequently the piston in the larger bore will act as a pump, forcing air into the storage tank. This action will also occur at any time when the

pressure in the chamber 25 is greater than that in the storage tank, which will tend to automatically keep the pressure of that tank up to the required point.

It will be seen that when the sleeve of the distributing valve is in running position the engine does not pump air appreciably to the tank; while in the starting position on every alternate compression stroke there is a pumping action. This function of the invention may be utilized as a brake in the case of automobile engines. By providing means directly connected to the sleeve 44, to rotate it to any desired position intermediate the running and starting positions, the air compression chamber becomes a brake of any desired retarding effect, and will effectively brake the engine, the power being shut off and the clutch to the driving wheels connected.

By the construction and operation above described, it will be seen that the engine starts readily by means of compressed air, which is introduced in such a way as not to interfere with the explosive gas, and into an entirely separate chamber from that in which the explosions occur, consequently the engine is free to start by explosion of a charge at any point, and without disconnecting the compressed air source which is being used for starting. After the engine has started, air which is compressed in the supplementary cylinder is alternately forced through the explosion chamber to thoroughly scavenge and cool it, and then through the hollow piston valves to cool them, also air is supplied to the explosion chamber, during the compression of the explosive charge therein. If the throttle is partially closed the charging stroke will not fill the explosion chamber with gas, but there will be a partial vacuum therein. Consequently when, on the succeeding compression stroke, the explosion chamber is connected to the air compression chamber, the pressure of the two will be equalized by the flow of air to the explosion chamber, and the latter will be filled with gas. The consequent movement of the piston will, therefore, give a fully compressed charge. This is a distinct advantage, since it is important that the charge be fully compressed before it is exploded. It has been found that even though this pressure be obtained by the addition of air, thus making a leaner mixture, the explosion will be quicker and the power generated will be greater than if the pressure were less, and the mixture more rich in fuel. By having the area of the air compressing piston larger than that of the driving piston air could be actually forced into the explosion chamber. In certain cases this may be desirable.

The passage of air through the cylinder

during the scavenging stroke insures that the new charge of gas will be absolutely clean, that is, unmixed with burnt gases, which is highly important, and which secures a more complete combustion and a great saving in fuel, also the interior of the engine is cooled by this passage of air. With the cooling of the exhaust valve by the additional air which is forced through it, the parts which are most exposed to heat are sufficiently cooled to render this engine very suitable for air cooling throughout, and only in extraordinary cases will water cooling be necessary.

15 Many other advantages of my construction will be obvious to those familiar with this art.

I claim:

1. In a four-cycle explosive engine, the combination of a cylinder having a larger and a smaller bore, a double diameter piston having a head in each of the bores, an inlet for an explosive charge to the smaller bore, and an exhaust port for exploded gases therefrom, an inlet for air to the larger bore, a hollow piston valve controlling the inlet port of the smaller bore and having an opening adapted to register with the inlet, and means to lead air from the larger bore therethrough into the explosion chamber during the compression strokes of the piston.

2. In a four-cycle explosive engine, the combination of a cylinder having a larger and a smaller bore, a double diameter piston having a head in each of the bores, an inlet for an explosive charge to the smaller bore, and an exhaust port for exploded gases therefrom, an inlet for air to the larger bore, a hollow piston valve controlling the inlet port of the smaller bore and having an opening adapted to register with the inlet, and means to lead air from the larger bore therethrough into the explosion chamber while the exhaust port is closed.

45 3. In a four-cycle explosive engine, the combination of a cylinder having a larger and a smaller bore, a double diameter piston having a head in each of the bores, an inlet for an explosive charge to the smaller bore, and an exhaust port for exploded gases therefrom, an inlet for air to the larger bore, a hollow piston valve controlling the inlet port of the smaller bore and having an opening adapted to register with the inlet, and means to lead air from the larger bore therethrough into the explosion chamber while the exhaust port is open.

4. A four-cycle explosive engine comprising a cylinder, a piston therein, an inlet port for an explosive mixture and an outlet port for exploded gases, hollow piston valves controlling the inlet and outlet ports, means to actuate the piston valves to admit an explosive charge to the cylinder and to allow ex-

haust of exploded gases therefrom, a source of compressed air connected to the inside of the valve controlling the inlet port and a lateral opening in said valve adapted to register with the inlet port when the outlet port is open whereby to force air through the valves and across the explosion chamber to cool them.

5. A four-cycle explosive engine comprising a cylinder, a piston therein, an inlet port for an explosive gas, an exhaust port for exploded gas, a piston valve controlling the inlet port comprising a hollow cylinder having an opening adapted to register with the inlet port, another opening adapted to register with a port from a source of compressed air, and means to reciprocate the piston valve to open and close the inlet port and to intermittently admit air to the cylinder.

6. A four-cycle explosive engine comprising a cylinder, a piston therein, an inlet port for an explosive gas, an exhaust port for exploded gas, a piston valve controlling the inlet port comprising a hollow cylinder having an opening adapted to register with the inlet port, another opening adapted to register with a port from a source of compressed air, and means to reciprocate the piston valve to open and close the inlet port and during the compression and scavenging strokes of the piston admit air to the cylinder.

7. A four-cycle explosive engine comprising a cylinder, a piston therein, an inlet port for an explosive gas, an exhaust port for exploded gas, a piston valve controlling the inlet port comprising a hollow cylinder having an opening adapted to register with the inlet port, another opening adapted to register with a port from a source of compressed air, and means to reciprocate the piston valve to open and close the inlet port and during the compression stroke of the piston admit air to the cylinder.

8. A four-cycle explosive engine comprising a cylinder, a piston therein, an inlet port for an explosive gas, an exhaust port for exploded gas, a piston valve controlling the inlet port comprising a hollow cylinder having an opening adapted to register with the inlet port, another opening adapted to register with a port from a source of compressed air, and means to reciprocate the piston valve to open and close the inlet port and while the exhaust port is open admit air to the cylinder.

9. A four-cycle explosive engine comprising a cylinder having a larger and a smaller bore, a double diameter piston working in the bore, an inlet port for explosive gas to the smaller bore and an exhaust port for exploded gas therefrom, hollow piston valves controlling the inlet and exhaust ports and having openings adapted to register with

- passages to the larger bore, and connections to actuate the piston valves to admit air compressed in the larger bore to the explosion chamber during the compression strokes of the piston.
10. A four-cycle explosive engine comprising a cylinder having a larger and a smaller bore, a double diameter piston working in the bore, an inlet port for explosive gas to the smaller bore and an exhaust port for exploded gas therefrom, hollow piston valves controlling the inlet and exhaust ports and having openings adapted to register with passages to the larger bore, and connections to actuate the piston valves to open the exhaust port and to admit air from the larger bore into the explosion chamber during the scavenging stroke of the piston.
11. A four-cycle explosive engine comprising a cylinder having a larger and a smaller bore, a double diameter piston working in the bore, an inlet port for explosive gas to the smaller bore and an exhaust port for exploded gas therefrom, hollow piston valves controlling the inlet and exhaust ports and having openings adapted to register with passages to the larger bore, and means to close the exhaust port and to admit air from the larger bore to the explosion chamber during the compression stroke.
12. A four-cycle explosive engine comprising a cylinder having a larger and a smaller bore, a double diameter piston working in the bore, an inlet port for explosive gas to the smaller bore and an exhaust port for exploded gas therefrom, hollow piston valves controlling the inlet and exhaust ports and having openings adapted to register with passages to the larger bore, connections to actuate the valves to admit an explosive charge to the smaller bore and to exhaust burnt gases therefrom, and means to force air compressed in the larger bore through the valves to cool them.
13. A four-cycle explosion engine comprising a cylinder having a larger and a smaller bore, a double diameter piston working in the bore, an inlet port for explosive gas to the smaller bore and an exhaust port for exploded gas therefrom, hollow piston valves controlling the inlet and exhaust ports and having openings adapted to register with passages to the larger bore, connections to actuate the valves to admit an explosive charge to the smaller bore and to exhaust burnt gases therefrom, and means to force air compressed in the larger bore through the valves and the explosion chamber to cool them.
14. The combination with a multiple-cylinder explosive engine having inlet and exhaust valves, air compressing means associated with each cylinder, and an air distributing valve, of a chamber leading from the air compressing means to the distributing valve, said distributing valve comprising a perforated rotary sleeve, a rotary shaft inside the sleeve, passages through the rotary shaft adapted to register with the perforations in the sleeve, means connected to the engine shaft to rotate the valve shaft, and passages beyond the distributing valve adapted to lead air therefrom to a storage tank, and to the exhaust valves of the engine.
15. The combination with a multiple-cylinder explosive engine having inlet and exhaust valves and air compressing means associated with each cylinder, of an air storage tank and a distributing valve adapted to lead air compressed by the engine to the exhaust valves of the explosive chambers and to the storage tank, said distributing valve comprising a chamber connected to the air compressing means, a rotary sleeve having perforations therein forming outlets from said chamber, a rotary shaft inside the sleeve having passages cut therein adapted intermittently to register with the perforations in the surrounding sleeve, and other passages connected with said perforations beyond the rotary valve device leading to the exhaust valves of the engine and to the storage tank, respectively.
16. The combination with a multiple-cylinder explosive engine having inlet and exhaust valves and air compressing means associated with each cylinder, of an air storage tank and a valve adapted to distribute air compressed by the engine to the storage tank and to the exhaust valves of the engine, said distributing valve controlling a passage leading from the air compressing means and comprising a rotary sleeve having perforations therein forming outlets from said passage, a rotary shaft inside the sleeve having channels cut therein adapted to register with the perforations in the sleeve, passages beyond the sleeve connected to perforations therein and leading to the storage tank, and to the exhaust valves, and means to turn the rotary sleeve whereby to control the distribution of air therethrough.
17. In a multiple-cylinder explosive engine having air compressing means and inlet and exhaust valves associated with each cylinder, an air storage tank, a valve adapted to distribute air to the storage tank and to the exhaust valves of the explosive cylinders, said distributing valve comprising a rotary sleeve, having perforations therein, a chamber on one side of said sleeve connected to the air compressing means, passages on the other side of the sleeve connected to the storage tank and to the exhaust valves and to said perforations, a rotary shaft inside the sleeve having channels cut therein adapted to register with the perforations of the sleeve, means connected to the engine shaft to rotate the valve shaft, and manually operated means to shift the position of the 130

rotary sleeve whereby to control the distribution of air through said valve.

18. In combination with a distributing valve for air compressed by a multiple-cylinder explosive engine, said valve comprising a rotary sleeve having perforations therein, a rotary shaft inside the sleeve having passages therethrough adapted to register with said perforations, and passages leading from the perforations whereby to distribute the compressed air, means to control the position of the rotary sleeve comprising a gear wheel connected to the end of said sleeve, a rack engaging the wheel, a piston connected to said rack, a spring pressing the piston in one direction, and an air chamber adapted to exert pressure in opposition to the spring, a source of compressed air, a connection from said source to the piston chamber, and a pilot valve controlling the connection between the source of compressed air and piston chamber and manually operated means to control the pilot

valve whereby to shift the sleeve to control distribution of air pressure. 25

19. A device for controlling a rotary distributing valve for explosive engines comprising a perforated sleeve having a notched shaft adapted to be rotated in the sleeve, comprising a gear wheel attached to the end 30 of the sleeve, a rack engaging said gear wheel, a coil spring at one end of the rack, and a piston at the other end, connection from the end of the piston to a source of compressed air, a valve controlling the connection from the source of compressed air to the piston, and manually operated means to open said valve to admit air to actuate the piston against spring pressure to change the position of said rotary sleeve. 35 40

In testimony whereof I have hereunto set my hand.

JÖRGEN REMMEN.
